CLAIM

The ornamental design for a audio plug wrench, as shown and described herein.

DESCRIPTION

FIG. 1 is a front perspective view of the audio plug wrench according to an embodiment of the present disclosure.

FIG. 2 is a rear perspective view of the audio plug wrench shown in FIG. 1.

FIG. 3 is a side elevation view of the audio plug wrench shown in FIG. 1.

FIG. 4 is a top view of the audio plug wrench shown in FIG. 1.

FIG. 5 is a front elevation view of the audio plug wrench shown in FIG. 1.

FIG. 6 is a rear elevation view of the audio plug wrench shown in FIG. 1.

FIG. 7 is a front perspective view of a first variant of the audio plug wrench according to an embodiment of the present disclosure.

FIG. 8 is a side elevation view of a first variant of the audio plug wrench shown in FIG. 7.

FIG. 9 is a front perspective view of a second variant of the audio plug wrench according to an embodiment of the present disclosure; and,

FIG. 10 is a front perspective view of a third variant of the audio plug wrench according to an embodiment of the present disclosure.

1 Claim, 10 Drawing Sheets
